(57) **CLAIM**

The ornamental design for a foam sprayer, as shown and described.

DESCRIPTION

FIG. 1 is a rear perspective view of a foam sprayer showing my new design;

FIG. 2 is a right-side elevation view thereof;

FIG. 3 is a top plan view thereof;

FIG. 4 is a left-side elevation view thereof;

FIG. 5 is a bottom plan view thereof;

FIG. 6 is a back elevation view thereof; and,

FIG. 7 is a front elevation view thereof.

The broken lines depict portions of the foam sprayer that form no part of the claimed design. In FIG. 5, the dot dash dot broken line denotes the boundary of the claim and forms no part thereof.

1 Claim, 6 Drawing Sheets
